HIS ATTORNEY

UNITED STATES PATENT OFFICE.

WILLIAM T. ALDRICH, OF MILLVILLE, MASSACHUSETTS, ASSIGNOR TO WOONSOCKET RUBBER COMPANY, A CORPORATION OF RHODE ISLAND.

CIRCULATION SYSTEM FOR VULCANIZERS.

1,288,464.

Specification of Letters Patent. Patented Dec. 24, 1918.

Application filed June 20, 1916. Serial No. 104,654.

To all whom it may concern:

Be it known that I, WILLIAM T. ALDRICH, a citizen of the United States, residing at Millville, in the county of Worcester and 5 State of Massachusetts, have invented certain new and useful Improvements in the Circulation Systems for Vulcanizers, of which the following is a full, clear, and exact description.

10 This invention relates to vulcanizing apparatus, and more particularly to apparatus for circulating the vulcanizing medium in a vulcanizer.

One type of vulcanizer in general use, is 15 provided with heating pipes on the sides, rear end and door. To uniformly heat the vulcanizing medium, such as CO₂, a greater steam pressure is usually maintained in some of these pipes than in others. The present 20 invention obviates this as well as the necessity for steam pipes on the rear end and on the door of the vulcanizer.

The invention can be readily understood 25 from the following description taken in connection with the accompanying drawing in which the figure is a longitudinal sectional view with parts in elevation, showing apparatus embodying my improvements.

In carrying out the invention, a shell 10 30 of similar shape and of smaller diameter than the vulcanizer 11, is disposed within the vulcanizer, and lies inside of the steam pipes 12. The shell is open at the end which confronts the door 13 of the vulcanizer, to 35 permit rubber articles on their forms, such as for instance, a car of lasted rubber boots or shoes, being run into the shell. The shell is provided with an opening 14 in the center of the rear end, and mounted in the 40 opening 14 is a fan 15, in the present embodiment, the blades of the fan being disposed to suck the vulcanizing medium, such as for instance CO₂, longitudinally through the shell and expel it through the vulcanizer 45 outside of the shell around the steam pipes. Thus the vulcanizing medium is passed over the hot steam pipes continually and is uniformly heated throughout.

Moreover, the course of the heated vul- 50 canizing medium through the vulcanizer in one direction and through the shell in the opposite direction as indicated by the arrow heads, necessitates the positive passage of the medium across the door and across the 55 rear end of the vulcanizer. Thus these

parts, which are usually cooler than the rest of the vulcanizer and require additional steam pipes, are maintained at the same temperature as the rest of the vulcanizer. Hence the steam pipes on the door and on 60 the rear end of the vulcanizer may be dispensed with. Furthermore, when this circulating apparatus is in use, it has been found that the same steam pressure may be maintained in all of the steam pipes, so that 65 the usual manual attention, and the usual control apparatus for the steam pipes, may be to a great extent dispensed with.

In operation, the articles to be vulcanized 70 are placed within the shell 10 which forms a compartment that houses them during the vulcanizing operation. If desired, the vulcanizer may be evacuated by withdrawing the air therefrom through the exhaust pipe 19 before the vulcanizing medium, under 75 pressure or not, is admitted through the pipe 20. Steam is then admitted to the pipes 12 to heat the vulcanizing medium to the vulcanizing temperature. The fan is now started, or may be started at or prior 80 to turning on the steam, and operates to suck the vulcanizing medium longitudinally through the shell and expel it outside of the shell longitudinally through the vulcanizer and around the pipes. The vulcanizing medium is thus uniformly heated and carried to all parts in the vulcanizing chamber or shell so that uniform density and a uniform degree of vulcanization throughout 85 all parts of the rubber articles will be produced.

In the present embodiment the fan is provided with a shaft 16, which is revolvably mounted in a suitable bearing 17 formed in the rear end of the vulcanizer, and which 90 is terminally equipped outside of the vulcanizer with a pulley 18, to which power may be applied for driving the fan. However, any preferred mechanism for driving the fan may be substituted for that shown.

Having thus described my invention, what I claim as new and desire to protect by Letters Patent is:

1. An apparatus of the class described comprising a chamber for vulcanizing goods 105 therein, said chamber being open at one end for receiving the goods to be vulcanized, a closure for said opening, means for heating the chamber, a chamber exterior to and surrounding the first chamber to provide a 110

jacket for said first chamber, said chambers being in communication with each other through remotely positioned openings, and means for circulating the vulcanizing medium from one chamber to the other in a continuous direction through said communicating openings.

2. An apparatus of the class described comprising a chamber for vulcanizing goods therein, said chamber being open at one end for receiving the goods to be vulcanized, a closure for said opening, a chamber exterior to and surrounding the first chamber to provide a jacket for said first chamber, said chambers being in communication with each other through remotely positioned openings, means for circulating the vulcanizing medium from one chamber to the other in a continuous direction through said openings, and means disposed in said second chamber for heating the medium.

3. An apparatus of the class described

comprising a horizontally disposed cylindrical inner shell forming a chamber for containing goods to be vulcanized, and open at each end, a second shell exterior to and surrounding the first shell and spaced therefrom to provide a chamber therebetween open at the receiving end of the vulcanizer, a closure for said opening spaced from said first shell when in closed position, a shaft extending through the wall of the exterior shell, a pulley mounted on the outer end of said shaft for driving same, and a fan mounted on the inner end and within the opening of said inner shell opposite the receiving end for circulating the vulcanizing medium from one chamber to the other in a continuous direction through the openings in said inner shell.

Signed at Millville, Massachusetts, this 16th day of June, 1916.

WILLIAM T. ALDRICH.
